UNITED STATES PATENT OFFICE.

CECIL H. BALMAT, OF SAN FRANCISCO, CALIFORNIA, ASSIGNOR, BY MESNE ASSIGNMENTS, TO STANDARD OIL COMPANY OF CALIFORNIA, OF SAN FRANCISCO, CALIFORNIA, A CORPORATION OF DELAWARE.

FURNACE.

Application filed June 2, 1925. Serial No. 34,364.

This invention relates to a furnace for burning fuel oils, especially heavy fuel oils, and while the furnace may be adapted for other purposes, it is particularly intended 5 to be useful as a domestic heating furnace. In order to burn heavy fuel oil satisfactorily it is necessary to effect a suitable atomization of the fuel, to provide the correct quantity of air, and to maintain the proper temperature 10 during combustion. The burners which are used in industrial plants for burning heavy oils are usually either of a type in which steam, or sometimes air, under high pressure is utilized to atomize the oil; or, of 15 a type in which the oil is broken up by mechanical means, either by being forced to issue from a small orifice or from the periphery of a rapidly revolving cup. In domestic installations, steam under high pressure 20 is not available; neither is compressed air, and furthermore, burners using these means for atomization are noisy in operation and require exact control, preferably by an expert. Burners using mechanical means 25 for effecting the pulverization of the fuel are, in general, not very flexible under domestic conditions—that is, they have poor ability to change from a small to a large fire efficiently. Furthermore, they require con- 30 siderable cleaning. Those burners which utilize pressure alone for the atomization of the oil require high pressure pumps and in small sizes, such as would be suitable for domestic use, the orifices are necessarily so 35 small as to become very easily stopped up. One of the difficulties in burning oil in a domestic furnace lies in the fact that the shape and proportions of the furnace ordi- 40 narily available are such as to require a very short length of flame, that is, extremely rapid combustion; moreover, the usual furnace will not hold the heat at low burning rates sufficiently to effect proper combustion. In order to burn heavy fuel oils successfully 45 in the usual domestic furnace, therefore, it is necessary to effect the most thorough atomization of the fuel in order to bring the flame length into the practical limits im- 50 posed by the space available. As just pointed out, this thorough atomization necessitates the use of complicated means, and, in general, is very difficult to effect in domestic installations. These difficulties obtain primarily because little or no attention

has been given to the proper shape and de- 55 sign of the furnace firebox and its relation to the burner.

The general object of this invention is to produce a furnace of simple construction in which the requisite temperature conditions 60 are always maintained, even for the smallest fires, and operating in such a way that the gases during combustion pass through a relatively long path; also to provide a construction in which the flame or gas during 65 combustion is caused to reverberate within the firebox, at the same time providing means for protecting the burner from direct im- 70 pingement of the reverberating flame; also to provide means for producing a regenerating 75 effect within the firebox, by directing the reverberated flame along the same path as the flame issuing from the burner; also to provide means for confining the flame more or less to the immediate vicinity of the fire- 80 box; also to provide a furnace of relatively small volume constructed entirely of refrac- 85 tory material which becomes highly heated and radiates or throws back a large amount of heat to the fire; and by this construction to permit the use of relatively simple means for atomization, or to increase materially the efficiency and flexibility of burners utilizing more complicated means.

A further object of the invention is to pro- 85 vide a construction in which the fuel oil is sufficiently heated to enable it to flow freely to the burner tip, and to assist its atomization, but in which the fuel is sufficiently pro- 90 tected from the furnace heat to prevent its volatilization before it reaches the tip of the burner.

Further objects of the invention will appear hereinafter.

The invention consists in the novel parts 95 and combination of parts to be described hereinafter, all of which contribute to produce an efficient furnace.

A preferred embodiment of the invention is described in the following specification, 100 while the broad scope of the invention is pointed out in the appended claims.

In the drawings:

Fig. 1 is a diagrammatic view showing in side elevation a furnace embodying my invention, the upper portion of the furnace being broken away.

Fig. 2 is a horizontal section through the

fire box, taken about on the line 2—2 of Fig. 1.

Fig. 3 is a cross section taken through the furnace above the fire box on the line 3—3 of Fig. 1.

Fig. 4 is a vertical section taken through the fire box on the line 4—4 of Fig. 3.

Fig. 5 is a vertical section at the side of the fire box wall and showing a modified embodiment for the face of this wall to increase the conduction of heat into the furnace wall.

Fig. 6 is a horizontal section through a portion of the fire box wall and showing another embodiment of the idea disclosed in Fig. 5.

Fig. 7 is a vertical section through the wall of the fire box and showing a portion of the burner in section, the rest of the burner being shown in elevation and the connection to it broken away. This view is upon an enlarged scale.

Fig. 8 is a vertical section taken on the line 8—8 of Fig. 7 illustrating details of the locking means for holding the fuel pipe in any adjusted position.

Fig. 9 is a longitudinal section illustrating a modified embodiment of the burner nozzle.

Fig. 10 is a front elevation of the burner shown in Fig. 9.

Fig. 11 is a longitudinal section showing another embodiment of the burner.

Fig. 12 is a front elevation of the burner shown in Fig. 11.

Fig. 13 is a plan of the tip of the fuel pipe shown in Fig. 7.

Fig. 14 is a side elevation of the tip shown in Fig. 13.

Fig. 15 is a horizontal section through the fuel pipe tip taken about on the line 15—15 of Fig. 14.

The furnace 1 which is illustrated is of the upright type, with a fire box 2 at its lower end and a combustion chamber 3 above the fire box. In applying my invention to a furnace of this type, I provide means for admitting an air blast and fuel at one side of the fire box, and I construct the fire box in such a way as to effect a reverberation of the flame or gases during combustion in a substantially horizontal plane so that they are made to flow back to the end of the fire box where the fuel and air are admitted. I also provide means for protecting my burner from direct impingement of the flame. This reverberation of the gases during combustion is preferably accomplished in such a way as to divide the flame or gases into two currents which return to the front of the fire box along the face of the fire box wall. The fire box is also provided with regenerator means adjacent the burner which also operates to assist in protecting the burner from impingement of the flame.

In order to accomplish this, I provide a burner 4 which operates as an air duct or air nozzle 5. This nozzle 5 is of relatively large diameter and carries within it a fuel pipe 6 which in the present instance is constructed to carry a relatively heavy oil fuel. The oil pipe 6 is preferably located centrally in the air nozzle so that it is insulated by the air blast from the temperature in the fire box wall 7 in which the burner 4 is mounted; this burner is constructed so that although sufficient heat reaches the pipe to enable the oil to flow freely in the coldest weather, at the same time it is sufficiently insulated due to the construction of the burner that the oil passing through the pipe will not become volatilized. The air nozzle 5 preferably has a tapered or conical tip 8, and the tip 9 of the fuel pipe preferably projects a fraction of an inch through the orifice of the air nozzle (see Fig. 7). The forward end of the oil pipe may be supported in a cross bar 10 which passes diametrically across the air nozzle. The pipe 6, however, is adjustable through this arm or bar 10. The air blast is preferably furnished by a fan or blower 11 which may be driven by an electric motor 12. The air is preferably at a relatively low pressure.

Any suitable means may be employed for controlling the flow of the air blast to the burner, for example, a valve 13 may be provided which in the present instance is located between the blower and the burner. By closing this valve more or less, the amount of air flowing to the burner may be nicely regulated. This valve may be of any desired type.

The fuel oil may be supplied through a flexible pipe 14 which admits the oil through a valve 15 at the back end of the fuel pipe 6. At its outer end, the fuel pipe is carried in a bushing 16 which is screwed into the back of the air nozzle and suitable means may be provided for locking the fuel pipe 110 and bushing in any adjusted position. For this purpose, the bushing 16 may have an extension or neck 17 at its inner end with a longitudinal groove 18 which may receive a set-screw 19 (see Fig. 8).

Referring again to the fire box 2, the wall opposite to the burner is provided with means, for example a ridge or abutment 22, extending in a vertical direction, which is located on the axis of the burner, and this ridge operates to divide the gases during combustion, or the flame, into two currents, as indicated by the arrows in Fig. 2; in other words, the inner end of the fire box is constructed with a grooved face 20 at each side which guides the flame back toward the front of the fire box.

I provide suitable means to prevent this flame from impinging on the burner, and this function is performed by regenerator 130

means in the form of a tunnel 21 between two regenerator walls 23 disposed on opposite sides of the tunnel. Back of each wall 23 is a flue 24 through which the gases or flames pass; at a point near the nozzle, and on each side of the nozzle, the wall of the fire box is provided with curved guide faces 25 which bend the flame or gases during combustion toward the back of the furnace. In other words, this end of the fire box is shaped so as to deflect the flame forwardly and over the burner so that it also assists the regenerator in protecting the burner from the flame.

When the furnace is in operation, of course the regenerator walls 23 become very highly heated, and if any drops of oil fail to be atomized sufficiently and fall upon the faces of these walls 23, they will be immediately ignited or will be taken up again by the current of gases passing these faces.

The furnace is preferably provided with means operating to confine the gases during combustion more or less to the fire boxes. Any suitable means may be provided for this purpose, but in the present instance I merely provide the inner face of the furnace wall with a coping 26 which projects horizontally into the furnace chamber and divides the fire box from the combustion chamber 3 above it. This coping extends further out into the fire box at the end of the fire box which is located near the burner, so that it extends over the regenerator walls 23 and assists in forming the return flues 24.

In starting up a furnace with a heavy fuel oil, it is sometimes necessary to provide special means for igniting the oil and warming up the burner. This may be accomplished if desired by throwing some oil-soaked waste into the furnace, or, if desired, a gas connection 27 may be run into the back part of the furnace. If desired, the connection 27 may be used after starting the furnace for delivering an additional supply of air, or other connections may be used at other points in the furnace for admitting additional air for combustion.

The tip 9 may have any form or construction desired, and steam, air, mechanical, or other means may be used to effect the desired atomization of the fuel; I prefer, however, to utilize a low pressure air blast for atomizing the fuel and to construct the tip so that it has the features illustrated in Figs. 13 to 15. This tip is produced by swaging out the end of the oil pipe to the shape of a funnel and then flattening it to a fan-shaped outline. Between the two sides a narrow slot is left, and this capillary space is kept intact during the remaining operations by any suitable means, but most conveniently by the insertion of a triangle of thin sheet metal, which is withdrawn when the work is finished. The tip is then rolled about a longitudinal axis so that, looking on the end,

the slot becomes circular in form. One of the sides thus is made into the inner wall or tongue 28, and the other becomes the outer wall and a continuation of the pipe. By this operation, the points 29 of the flattened tip are rolled together over the tongue so that they meet as at the point 30, in Fig. 13. In this way, directly over the tongue 28, an air duct 31 is formed through which the air blast flows as indicated by the arrow 75 in Fig. 13; the effect is to provide a narrow grooved throat 32 (see Fig. 15) into which the oil will pass by capillary attraction. This enables the tip to operate effectively although there may be a very small 80 quantity of oil arriving at the tip.

In order to increase the heat radiating surface of the furnace wall, I may provide the interior of the fire box with horizontal corrugations 33 (see Fig. 5) or I may provide 85 it with corrugations 34 (see Fig. 6), vertically. The form of corrugations shown in Fig. 5 seems to be preferable, however, because it does not impede or produce eddy currents in the flame as it passes along the side walls of the fire box; at the same time it would produce a very intimate contact between the flame and the fire box wall, enabling the wall to absorb a very considerable quantity of the heat in the gases or 95 flame.

Other types of fuel pipe tips or nozzles are illustrated in Figs. 9 to 12. In the form shown in Fig. 9, the end of the fuel duct or fuel pipe 35 is bent up and formed into 100 an annular nozzle 36 into which a bushing 37 may be screwed from the rear. This bushing 37 carries an air duct 38. The bushing 37 is of slightly smaller diameter than the nozzle 36, so that a narrow annular 105 space 39 is formed around the bushing which may, if it is small enough, exert capillary attraction on the oil.

In the type of burner or oil pipe tip shown in Fig. 11, the pipe 40 is drawn down into a 110 tapered end or spear 41 which passes into the center of an air nozzle 42 to which it is connected. A passage 43 leads from the interior of the spear into a conical annular space 44 around the nozzle 42, this space is 115 formed by screwing on the nozzle 42 an outer nozzle 45 of conical form.

It is evident that in the operation of this furnace, the construction of the fire box is such as to guide the flame or gases during 120 combustion in a relatively long path within the fire box. At the same time, a regenerator effect is produced, though the burner is protected from impingement of the flame.

The fire-box, of course, may be constructed 125 of fire clay, fire brick, or any other suitable refractory material.

It is understood that the embodiment of the invention described herein is only one of the many embodiments this invention may 130

take, and I do not wish to be limited in the practice of the invention, nor in the claims, to the particular embodiment set forth.

What I claim is:—

- 5 1. In a furnace for burning heavy oils, the combination of a fire-box, an air-duct mounted in the fire-box wall, a fuel-oil pipe extending longitudinally through the air-duct and projecting at its inner end beyond the end of the air-duct, said air-duct being of relatively large diameter whereby the fuel pipe within the same is insulated from the high temperature of the fire-box wall, and regenerator means located in the fire-box adjacent the burner, said fire-box having means for effecting a reverberation of the gases during combustion past the regenerator means. 70
- 10 2. In a furnace for burning heavy oils, the combination of a fire-box, an air-duct mounted in the fire-box wall, a fuel-oil pipe extending longitudinally through the air-duct and projecting at its inner end beyond the end of the air-duct, said air-duct being of relatively large diameter whereby the fuel pipe within the same is insulated from the high temperature of the fire-box wall, and regenerator means located in the fire-box adjacent the burner, said fire-box having means for effecting a reverberation of the gases during combustion past the regenerator means, said fuel pipe being disposed substantially centrally within the air duct, whereby the airblast surrounding the fuel pipe operates to cool, and insulate the same from the high temperature of the fire-box wall. 75
- 15 3. A furnace for burning heavy fuel oils having a burner constructed to operate with a low pressure air blast, and operating to atomize oil with the air blast and direct the same across the fire-box of the furnace, a combustion chamber above the fire-box, said fire-box having a ridge in its wall opposite the burner to divide the burning gases and effect a reverberation thereof by directing the same in two currents in the same horizontal plane and passing along the face of the side walls of the furnace back toward the burner, said fire-box having means projecting in from the wall above the currents of gases operating to confine the same within the fire-box, a regenerator device at each side of the nozzle in a position to become highly heated by the flame from the burner, and covered tunnels on the outer sides of the regenerator devices receiving the said currents of gases passing along the walls of the fire-box, and means in the fire-box adjacent 80 the burner for deflecting the currents passing through the tunnels forwardly past the burner and between the regenerator devices. 85
- 20 4. A furnace for burning heavy fuel oils having a burner constructed to operate with a low pressure air blast, and operating to atomize oil with the air blast and direct the same across the fire-box of the furnace, a combustion chamber above the fire-box, said fire-box having a ridge in its wall opposite the burner to divide the burning gases and effect a reverberation thereof by directing the same in two currents in the same horizontal plane and passing along the face of the side walls of the furnace back toward the burner, said fire-box having means projecting in from the wall above the currents of gases operating to confine the same within the fire-box, a regenerator device at each side of the nozzle in a position to become highly heated by the flame from the burner, and covered tunnels on the outer sides of the regenerator devices receiving the said currents of gases passing along the walls of the fire-box, and means in the fire-box adjacent 90 the burner for deflecting the currents passing through the tunnels forwardly past the burner and between the regenerator devices. 95
- 25 5. A fire box having means for effecting reverberation of the flame in a substantially horizontal plane, and having corrugations on the inner face of the wall in contact with the flame. 100
- 30 6. A furnace for burning heavy fuel oils having a burner constructed to operate with a low pressure air blast and operating to atomize oil with the air blast and direct the same across the fire-box of the furnace, a combustion chamber above the fire-box, said fire-box having a ridge in its wall opposite the burner to divide the burning gases and effect a reverberation thereof by directing the same in two currents in the same horizontal plane and passing along the face of the side walls of the furnace back toward the burner, said fire-box having means projecting in from the wall above the currents of gases operating to confine the same within the fire-box, a regenerator device at each side of the nozzle in a position to become highly heated by the flame from the burner, and covered tunnels on the outer sides of the regenerator devices receiving the said currents of gases passing along the walls of the fire-box, and means in the fire-box adjacent 105 the burner for deflecting the currents passing through the tunnels forwardly past the burner and between the regenerator devices. 110
- 35 7. A furnace for burning heavy fuel oils having a burner constructed to operate with a low pressure air-blast and operating to atomize oil with the air-blast and direct the same across the fire-box of the furnace, a combustion chamber above the fire-box said fire-box having a regenerator wall on each side of the burner, disposed in a substantially vertical plane and extending longitudinally with the axis of the burner, said fire-box having covered flues on the outer sides of the regenerator walls forming covered tunnels for directing the flame back toward the forward wall of the fire-box, the forward wall of the fire-box having means on each side of the burner for deflecting the currents passing through the said flues, past the burner and between the regenerator walls and toward the rear wall of the furnace. 115
- 40 8. In a furnace for burning heavy fuel oils, the combination of a burner constructed to operate with a low pressure air-blast and operating to atomize oil with the air-blast and direct it across the fire-box of the furnace, a combustion chamber above the fire-box, the back wall of the fire-box operating to divide the current of flame from 120 the burner and between the regenerator walls and toward the rear wall of the furnace. 125
- 45 9. In a furnace, the combination of a fire-box and a combustion chamber above the fire-box, a nozzle for admitting the fuel, a regenerator adjacent the nozzle with a regenerator wall on each side of the nozzle 130
